VENDING MACHINE

Charles V. Vanbergen, Lowfield Park, near Crawley, England

Application October 30, 1936, Serial No. 108,336
In Great Britain March 5, 1936

5 Claims. (Cl. 312—66)

This invention relates to vending machines and particularly to machines for vending cartons of ice cream or the like from a refrigerated chamber or magazine constituting a part of the machine.

An object of the invention is to provide a vending machine for goods of the aforesaid character which is simple in construction and operation, and more particularly to provide new and improved means for transferring the goods from the magazine to the delivery aperture of the machine.

The invention provides a lifting device for cartons or the like stored in the magazine, the lifting device being operated by a winch which is actuated to cause the lifting device to raise a carton out of the magazine, the carton being subsequently released in position to pass to the delivery aperture of the machine and the winch drum being freed to enable the lifting device to return to its initial position.

One particular embodiment of the invention will now be described, by way of example, with reference to the accompanying drawings where-

25 in:—

Fig. 1 is a broken front elevation of a machine for vending cartons of ice cream incorporating the features of my invention;

Fig. 2 is a side elevation of the machine shown 30 in Fig. 1; and

Fig. 3 is a plan view thereof.

The machine illustrated in the drawings is of duplex construction, having two lifting devices 1 and two winches 2 operated from a single electric motor 3 to deliver the cartons 4 from two refrigerated chambers or magazines 5. The electric motor 3 which operates the machine is secured to a platform 6 carried by vertical guides 7 for the lifting devices and is fitted with a reduction gear 8 driving a shaft 9 to which a pinion 10 is keyed. This shaft also has swivelly mounted thereon a bracket 11 carrying a second pinion 12 in mesh with the pinion 10. The bracket 11 is loose to swing in either direction 45 with the pinions 10 and 12 constantly in mesh. Mounted on the platform 6 on opposite sides of the pinions 10 and 12 are winches 2 the cables 13 of which are attached to the lifting devices or hoists 1. Each winch 2 has a gear 14 with which 50 the pinion 12 may be brought into mesh in a manner hereinafter described.

Each hoist 1 consists of an inverted U-shaped bracket 15 the depending parts 16 of which have projections 17 which run in the vertical guides 55 7. On the inside of each depending part 16 are

pivoted levers 18 which normally fall inwardly about their pivots from a vertical position to within 30° of the horizontal. On the top of each hoist 1 and facing inwardly is a projecting arm 19 which operates the striker 20 to be described.

A mechanism constituting a driving gear lock designated generally by the reference 25 is mounted on a fixed member 26 between the two inside hoist guides 7 and comprises a central boss 27 mounted on a pivot pin 28. Secured to the boss 27 are two horizontal arms 29 and a vertical arm 30. The latter is crank shaped as shown in Fig. 2 and engages in a recess in the bottom of the bracket 11. A latch 31 for the driving gear lock 25 is suspended from a bracket 32, mounted on the fixed member 26, as shown in Fig. 2, and a lock lever 33 on the back thereof has a pin and slot coupling with a fork 34. The latter is connected through a connecting rod 35 with a lower fork 36 which engages in the striker 20.

The striker 20 comprises two discs 38 and 39 each having a gap 40 cut in its periphery and a radial slot 41 formed diametrically opposite the said gap. The discs 38 and 39 are mounted on shafts 42 and a cross pin 43 carried by the collateral parts of the lower fork 36 engages in the radial slots 41 of the discs as shown in Fig. 1. A tension spring 44 is located between a pin 45 projecting outwardly from the disc 39 and the shaft 42 of the other disc 38 whereby a snap action 30 past the centres is obtained.

The ice cream cartons 4 are contained in refrigerated chambers 5 in a magazine of the form shown in dotted lines in Fig. 2 whereby when they are fed in from the top they roll down to the mouth of the magazine ready to be picked up by the respective hoist 1. Bell crank levers 48 constitute coin mechanism trips, one end of each lever projecting over the respective hoist 1 as shown in Fig. 1 and the other end being attached to a latch on the coin mechanism switch (not shown).

A delivery chute 49 is provided to which the cartons are guided by guide rods 50, bent forwardly at 51 to insure discharge thereof as they reach the mouth of the delivery chute. An "empty" sign trip 52 may also be provided at the lower end of the device in position to be engaged by the hoist when the magazine is empty. This sign trip is adapted by means (not shown) to cause an "empty" sign to be displayed after the last carton has been discharged.

The operation of the machine is as follows:

Assuming the machine is at rest with both hoists 1 at the bottom of the guides 7 and resting

on the lowermost carton as shown in Fig. 2, the striker 20, gear lock 25 and lock latch 31 will be in the positions shown in Figs. 1 and 2, the disposition of the slots 41 in the striker discs 38 and 5 39 thereby throwing the forks 36 and 34 upwards to free the lock latch 31 so that the arms are free to move. With the various parts of the mechanism in the aforesaid positions and the driving gear in its neutral position a coin is inserted in one of the coin slots and this moves the motor switch to the "on" position, the switch being held by the aforesaid switch latch. As soon as the motor commences to turn the torque causes the loose bracket 11 to swing over and the pinion 12 to engage with one or other of the gears 14 on the respective winch 2 and to rotate the same to raise the corresponding hoist 1, the pivoted levers 18 of which engage beneath and support the carton to be delivered. The motor 3 is 10 so connected that it turns in either direction according to which switch is made, the respective switches being made by the insertion of a coin in the respective coin slots. According to which direction the inserted coin has caused the motor 20 to turn, the bracket 11 swings over to one or other side in Fig. 1 to mesh with the respective gear 14. In addition to causing the pinion 12 to mesh with one of the gears 14, the movement of the bracket 11 moves the vertical arm 30 of the 15 gear lock 25 engaged in the slot therein to tilt it about the pivot 27. The horizontal arms 29 are thereby tilted correspondingly, the arm on the same side as the hoist being operated moving downwards as will be readily understood. The 20 projecting arm 19 on the operative hoist, due to the ascent of the latter, engages in the gap 49 of the respective disc 38 or 39 of the striker and rotates the disc. The slot 41 of the disc, moving downwards, draws down the pin 43, lower fork 36, connecting rod 35 and upper fork 34, whereby the latch 31 is moved into position to lock the arms 29 when they are again shifted to horizontal position by the arm 19.

The continued ascent of the hoist 1 carries the 25 cartons to the mouth of the delivery chute 49 where it rolls off the levers 18. To insure the correct delivery of the carton to the chute 49 should the carton be stuck in the hoist, guide rods 50 are bent forward at 51, as shown in Fig. 2, whereby the carton is forced off the levers 50 18 opposite the chute 49. Immediately after the delivery of the carton to the chute 49, the projecting arm 19 strikes the lowered arm 29 of the gear lock and throws the driving pinion 11 into neutral position, the latch 31 falls into position 55 due to the arms 29 having returned to a horizontal position and locks the gears in neutral position. Simultaneously the hoist strikes the horizontal arm of the bell crank lever 48 of the coin mechanism trip to move the latch on the 60 coin mechanism switch to inoperative position and the switch returns to the "off" position. Meanwhile the next carton has rolled from the mouth of the magazine into position to be picked up by the hoist which descends by gravity; the 65 projecting arm 19 on the descending hoist engages the striker mechanism 20 to reverse the operation previously described, thereby unlocking the gear lock 25 and leaving it ready for the motor 3 to throw the pinion 12 into mesh 70 with one or other of the gears 14 when it is again started. The pivoted levers 18 of the hoist take up a vertical position as the latter comes opposite the carton and then fall inwardly again as soon as they have passed, the final position 75 of the parts of the hoist being as shown at the

bottom of Fig. 2. When the last carton has been removed from either magazine the horizontal part of the hoist in descending does not abut a carton and consequently descends further than if a carton were present and contacts with an "empty" 5 sign trip 52. This lowers a plate over the respective coin slot and prevents any coins being inserted until the magazine has been reloaded.

Although a particular embodiment of the invention has been shown for purposes of illustration, it is to be understood that various changes and modifications may be made therein as will be apparent to a person skilled in the art. The invention is only to be limited in accordance with the following claims when interpreted in view of 10 15 the prior art.

The invention claimed is:

1. In a vending machine having a delivery aperture and a storage magazine for cartons or the like to be vended, a lifting device for said 20 cartons comprising a hoist having means to successively remove the cartons from said magazine and to deliver the same to said delivery aperture, a winch connected to raise said lifting device, a gear driving said winch, a motor-operated 25 driveshaft carrying a pivoted bracket, a pinion mounted on said bracket and driven by said shaft, said pinion being normally disengaged from said gear and being shiftable into driving engagement with said gear by the torque produced by 30 rotation of said shaft, and means actuated by said lifting device at the upper limit of its path of travel to disengage said pinion from said gear and to maintain said pinion in the disengaged position, whereby the driving connection is broken 35 and the lifting device is permitted to return by gravity to its initial position.

2. In a vending machine having a pair of delivery apertures and a pair of storage magazines for cartons or the like to be vended, a lifting device for successively removing cartons from each of said magazines and delivering the same to the respective delivery apertures, driving means including a driven gear for each of said lifting devices, a motor-operated driveshaft having a 40 bracket pivoted thereon, a pinion mounted on said bracket and driven by said driveshaft, said pinion being normally disengaged from said driven gears and being adapted to be swung into mesh with a selected gear by the torque produced 45 by the rotation of said driveshaft, means actuated by said lifting device to return said pinion to neutral position when said lifting device reaches the upper limit of its path of travel, means locking said pinion in neutral position during the 50 descent of said lifting device, and means associated with said lifting device to release said lock when the lifting device reaches the lower 55 limit of its path of travel.

3. In a vending machine having a pair of delivery apertures and a pair of storage magazines for cartons or the like to be vended, a lifting device for successively removing cartons from each of said magazines and delivering the same to the respective delivery apertures, driving means including a driven gear for each of said lifting devices, a motor-operated driveshaft having a bracket pivoted thereon, a pinion mounted on said bracket and driven by said driveshaft, said pinion being normally disengaged from said driven gears and being adapted to be swung into mesh with one or the other of said gears depending upon the direction of rotation of said driveshaft, means actuated by said lifting device at the upper limit 70 of its path of travel to return the pinion into 75

- neutral position, a gear lock adapted to automatically lock said pinion in neutral position during descent of the lifting device, control means for said gear lock operated by said lifting devices 5 at the lower limit of their paths of travel, said control means being engaged by a lifting device during ascent to render said gear lock operative to lock said pinion in neutral position, and being engaged during descent to release said lock 10 10 whereby the mechanism is free to operate when the driveshaft is again actuated.
4. In a vending machine having a pair of delivery apertures and a pair of storage magazines for cartons or the like to be vended, a separate 15 lifting device for successively removing cartons from each of said magazines and delivering the same to the respective delivery apertures, driving means including a driven gear for each of said lifting devices, a motor-operated driveshaft having a bracket pivoted thereon, a pinion mounted 20 on said bracket and driven by said driveshaft, said pinion being normally disengaged from said driven gears and being adapted to be swung into mesh with a selected gear, means comprising a vertical arm engaging said bracket and a horizontal arm connected thereto and adapted to be engaged by either of said lifting devices when the latter reaches the upper limit of its path of 25 travel for returning said bracket to neutral position, and means to lock said bracket in neutral position during the descent of said lifting device.
5. In a vending machine having a pair of delivery apertures and a pair of storage magazines for cartons or the like to be vended, a separate 5 lifting device for successively removing cartons from each of said magazines and delivering the same to the respective delivery apertures, driving means including a driven gear for each of said lifting devices, a motor-operated driveshaft having a bracket pivoted thereon, a pinion mounted 10 on said bracket and driven by said driveshaft, said pinion being normally disengaged from said driven gears and being adapted to be swung into mesh with a selected gear, means comprising a vertical arm engaging said bracket and a horizontal arm connected thereto and adapted to be engaged by either of said lifting devices when the latter reaches the upper limit of its path of 15 travel for returning said bracket to neutral position, and means to automatically lock said bracket in neutral position during descent of the lifting device and means actuated by said lifting device at the lower limit of its path of travel to release 20 said lock.

CHARLES V. VANBERGEN.
